(57) **CLAIM**

The ornamental design for the aircraft seat as shown and described.

DESCRIPTION

FIG. 1 is a front downward facing perspective view of the claimed design;

FIG. 2 is a front elevation view of the claimed design;

FIG. 3 is a rear elevation view of the claimed design;

FIG. 4 is a top plan view of the claimed design;

FIG. 5 is a right side elevation view of the claimed design;

FIG. 6 is a left side elevation view of the claimed design;

FIG. 7 is a right side elevation view of the claimed design in a reclined and folded orientation;

FIG. 8 is a bottom plan view of the claimed design;

FIG. 9 is a right side elevation view of the claimed design in a reclined and deployed orientation; and,

FIG. 10 is a top plan view of the claimed design in a reclined and deployed orientation.

The broken lines depict portions of the aircraft seat that form no part of the claimed design.

1 Claim, 10 Drawing Sheets
